INFANT TABLE RAIL

Harry W. Reece, Topeka, Kans.

Application July 19, 1948, Serial No. 39,555

1 Claim. (Cl. 5—3)

2

This invention relates to articles of furniture and, more particularly, to structure for confining infants, in the nature of an enclosure formed from a plurality of interconnected panels, the primary object being to provide rail structure capable of detachable mounting upon any table-like support, such as the conventional, well-known card table.

The most important object of this invention is the provision of rail structure having a plurality of panel-like, upright walls or railings all joined together and provided with means for securing to a card table in such manner as to be undisableable both laterally and vertically with respect to the table.

Another object of this invention is the provision of rail structure of the aforementioned character having a continuous internal groove formed adjacent its lowermost edge for receiving the edges of the table top, all to the end that the rail structure cannot be moved, to any appreciable extent with respect to the table, by the infant or others.

A further object of this invention is to provide a collapsible rail for confining infants, having a plurality of hinged interconnected panels, each of which panels is provided with a longitudinal groove adjacent the lowermost edge thereof for receiving corresponding edges of the top of a card table, at least two of the panels being provided with releasable elements for holding the entire rail structure clamped to the table.

Other more minor objects will be made clear as the following specification progresses, reference being had to the accompanying drawing, wherein:

Fig. 1 is a top plan view of an infant table rail, showing the same operably mounted upon a card table or the like.

Fig. 2 is a side elevational view thereof, parts being in section to reveal details of construction.

Fig. 3 is a fragmentary, perspective view of one corner of the rail structure; and,

Fig. 4 is a top plan view of a rail structure showing the rail per se in a partially collapsed condition.

The need has become apparent for rail structure adapted to confine infants within a predetermined area and, also, capable of being mounted upon a support in raised relationship to the floor. Those who care for small children particularly have found that the conventional play pen or infant's bed is impractical for many purposes, the former being too low to care for the infant without strenuous bending; and infant's beds being too deep to permit such care.

Furthermore, it is desirable to have a structure of this character that is entirely collapsible and, therefore, readily movable as desired by automobile or otherwise. Storage, also, is an important factor and this, together with the above-mentioned objects, are all embodied within the present invention.

The rail structure per se comprises a plurality of elongated polygonal panels 10, 12, 14 and 16, respectively. These panels are all of substantially the same character, constituting a normally uppermost longitudinal frame member 18 and a lowermost frame member 20. Frames 18 and 20 are substantially parallel and joined together by end posts 22 as well as by a plurality of spaced, intermediate posts 24. Posts 24 are preferably dowelled in place as indicated in Fig. 2 of the drawing, whereas, a mortise joint 30 of any suitable character is utilized to interconnect the end posts 22 and frame members 18 and 20.

The proximal ends of the two panels 10 and 12 are joined together by a pair of hinges 26, the uppermost hinge 26 only being shown in Figs. 1 and 4 of the drawing. The straps of these hinges 26 are secured flatly to the innermost faces of frame members 18 and 20 of such panels 10 and 12. A pair of hinges 28 of identical character to hinges 26 join together the proximal ends of panels 14 and 16 in the same manner.

A different type of hinge, however, is provided to join together and adjacent ends of panels 12 and 14, such hinge being disposed on that end of panels 12 and 14 opposite to hinges 26 and 28. This last-mentioned hinge structure is of a double-pin character and is broadly designated by the numeral 32.

One strap 34 of hinge 32 is secured directly to the end of panel 14, while the other strap 36 of hinge 32 overlies and joins with the outermost face of panel 12. An intermediate strap 38 joins hinged together the two straps 34 and 36. As illustrated in Fig. 3 of the drawing, there are, likewise, two of these hinges for the panels 12 and 14.

It is clear from the foregoing that the four panels may easily be moved from the substantially collapsed condition shown in Fig. 4 of the drawing to the fully extended positions shown by Figs. 1 and 2. Manifestly, the hinge structures 26, 28 and 32 permit movement of panels 10, 12, 14 and 16 to a substantially flat condition, not shown in the drawing.

The normally lowermost, elongated frame member 20 of each of the four panels is appreciably wider than the uppermost frame member

18. The normally innermost face of each of these frame members 20 is longitudinally grooved as at 40. Such grooves 40 extend the entire length of all frame members 20 and are preferably substantially midway between the longitudinal edges thereof.

Groove 40 should be sufficiently wide to accommodate top 42 of a conventional card table 44. It is well recognized that such card tables, in addition to top 42, are provided with collapsible legs 46, having angular corner braces 48. With groove 40 formed as above mentioned, when the rail structure is placed in use upon card table 44, a portion of the bottom of frame members 20 will overlap the uppermost edge of table top 42 and rest directly thereon. Similarly, a portion of frame members 20 will underly the marginal edge of table top 42.

Figs. 2 and 3 of the drawing illustrate the width of table top 42 as being slightly less than the width of the groove 40, which is satisfactory since, when the rail structure is so mounted, only a limited amount of upward movement can be imparted to the rail structure with respect to table top 42. Accordingly, it is possible to form groove 40 with a width that will accommodate virtually all types of card tables presently on the market.

The proximal ends of panels 10 and 16 are joined together after the rail structure is mounted upon the card table 44 by means of conventional hooks 50 and eyes 52 which, of course, may be easily unlatched to permit removal of the entire rail structure as desired. When the hooks 50 are in the operative position, illustrated in Figs. 1 and 2 of the drawing, all of the rails 10, 12, 14 and 16 will be held tightly clamped about the periphery of table top 42, preventing lateral displacement thereof with respect to table 44.

While the groove 40 is shown as substantially U-shaped in cross section, such contour may be varied to suit conditions. Similarly, the rail structure has been shown to accommodate a conventional, four-sided, substantially square card table but, here again, multi-sided rails may be provided for tables having more or less than four vertical side edges.

The particular height of the panels 10, 12, 14 and 16 may vary to suit conditions and in accordance with the strength and sturdiness of the card table or other supporting surface used. Most card tables are sufficiently strong to support the entire rail structure as well as the infant and whatever bedding is used; but, when the more stable tables are used, it is contemplated that the height of the railing be increased to accommodate larger children, if desired.

It is apparent that no fastening elements whatsoever are necessary to interconnect the rail structure with the table 44 other than the in-

herent clamping action that takes place when the panels are placed in circumscribing relationship to the table top 42 and the hooks 50 moved into place.

5 Since most homes have included in their furniture the usual type of card table, it is a simple matter to transport the rail structure by automobile for use with card tables of other homes, since the same are quite standard and the rail structure will readily fit the same. Obviously, 10 the length and width of the table top 42 will govern the lengths of the various side panels of the rail, the latter of which should be substantially the same as the length of the table top edge upon which it is mounted.

15 While only one embodiment of the present invention has been disclosed and specified, it is to be understood that many changes and modifications may be made without departing from the spirit of this invention as defined by the scope of the appended claim.

Having thus described my invention, what I claim as new and desire to secure by Letters Patent is:

20 25 In combination with a table having a polygonal top provided with a number of elongated side edges; a frame-like enclosure including a number of interconnected panels, each provided with a longitudinal member at the bottom thereof, there being a panel for each of said edges respectively, each member having a groove in its innermost face and extending throughout its length, the width of the grooves being greater than the thickness of the table top adapting the same to receive a portion of the table top adjacent a corresponding edge of the latter, with the enclosure completely circumscribing the table top, in partial overlapping relationship thereto, and for support thereby; releasable structure 30 35 40 45 joining one pair of said panels; and hinge means interconnecting all of said panels whereby the enclosure may be removed from the table top upon release of said structure and the panels folded into a stack.
